UNITED STATES PATENT OFFICE

2,259,031

WET DUST COLLECTOR AND AIR WASHER

Ernest F. Fisher, Boston, Mass.

Application January 30, 1939, Serial No. 253,551

2 Claims. (Cl. 261—21)

My invention relates to improvements in wet dust collectors and air washers, wherein the cleaning of the air is accomplished by subjecting it to the continuous scrubbing action of water or other liquid which is set in violent agitation by the swirling spiralling air and caused to wet and wash large surface areas upon which particles of dust are caused to impinge out of the air current.

This invention consists in the novel features of construction more fully set forth in the specifications and pointed out in the claims.

The principal object of my invention is to provide means whereby a more thorough wetting of the impingement surfaces is attained than those shown in my co-pending applications, Serial No. 251,751 filed Jan. 19, 1939, Serial No. 250,101, filed Jan. 10, 1939 and Serial No. 222,906 filed Aug. 3, 1938, and at the same time to provide a system of guide and impingement vanes or surfaces of a unitary structure that is independent of co-ordinating baffles and vanes and that can be withdrawn as a unit from the enclosing housing without hindrance from the cooperating baffles, vanes and other structural elements of the housing.

A further object of my invention is to provide a system of guide vanes, impingement surfaces, baffles and walls that impose the least resistance to the flow of dust laden air as it swirls spirally in a continuous path without change of direction, and to provide a structure that will facilitate fabrication and assembly and thus lowering the cost of this equipment to the purchaser.

Other advantages of this invention will be better apparent from a detailed description in connection with the accompanying drawing, in which Figure 1 is a vertical cross section taken on line 1—1 of Figure 2. Figure 2 is a horizontal section view taken on line 2—2 of Figure 1. Figure 3 is a vertical cross section of the axial tube T with its baffles and vanes. This is the assembly T shown in place in Figure 1 in cooperative relation with the baffles and vanes of housing 2.

The apparatus consists of a cylindrical shell or casing 2, provided at the top with a tangential inlet 15 which admits air or gases from which particles are to be removed. The casing is provided with a conical bottom 3 into which the particles, in the form of sludge, settle prior to their removal through the outlet 21. An outlet 14 for cleaned air or gases is provided in the casing.

A sludge cone, or collector, 1 is provided within

the casing and separates it into upper and lower compartments. The outlet in the bottom of this collector discharges into the vertical tube T. The outer surface of this tube is supplied with 5 a number of horizontal, downwardly sloping, circular baffles or plates, shown at 5^a, 5^b, 5^c and 5^d.

Around the periphery of each of these plates are arranged a number of swirl-producing means 18^a, 18^b, 18^c and 18^d. These consist of vertical 10 vanes curved about the horizontal axis as shown in Figure 2. It is to be understood that the vanes in alternate sets will be so arranged as to produce rotational movement of the gases in opposite horizontal directions. Thus, if the vanes 18^a and 18^c induce rotation in a clockwise direction, then the vanes 18^b and 18^d will induce rotation in a counterclockwise direction, and vice versa.

The unsupported ends of the vanes are reinforced by circular blade rings 20, 20^a, 20^b and 20^c, 20 the uppermost blade ring 20 being wider than the others for reasons to be shown below.

Within the lower compartment of the casing 2 are disposed a number of horizontal sloping baffles 6, 6^a, 6^b and 6^c, arranged in staggered 25 relationship to the plates 5^a, 5^b, 5^c and 5^d, but in cooperative alignment with blade rings 20, 20^a, 20^b and 20^c.

Figure 3 shows a unitary assembly composed of the vertical tube, baffle plates and swirl-producing vanes. This unit may be attached to the collector 1 by means of welding or otherwise and it is additionally supported within the casing by means of the blade ring 20 which overlaps the uppermost baffle 6, and is fastened by bolts k. 35 For purposes of cleaning or repair the entire unit may be removed after removing bolts k.

A liquid supply system 16 is attached to the top 19 of the casing, and another inlet for washing liquid, which may or may not be independent 40 of the first, is provided at 18'. This inlet leads to the annular liquid chamber 10, from which liquid drains through outlets 18' over the outer surface of the tube T and into the space between the tube T and outer shell 2.

Dust or fume laden air or both together enter the unit covered by plate 19, through tangential inlet 15 which causes the air to swirl in chamber 21. The swirling air breaks up the water issuing from pipes 16 and thoroughly wets the wall of chamber 21 which is a continuation of wall 2 of the chamber below. The heavy dust impinges on the wall of chamber 21 and is washed down into sludge cone 1 and then into axial tube T through which it passes into main sludge cone 18 formed 55 by wall 3. The air continues to swirl spirally

down the axial tube T and expands into chamber 17. While expanding into chamber 17 it continues to swirl and carries the water that falls down tube T and the water that falls off of tube baffle 5^c to wall 2 of chamber 17 thus wetting this wall and washing down dust that impinges thereon.

The air in chamber 17 then swirls up through curved vanes or blades 18^d which impart a further whirl to the air as it passes into space A. The water that falls through annular clearance 3 between baffle 6^c and tube baffle 20^c is carried through the vanes 18^d and copiously wets them and the adjacent wall of tube T. Some of the fine dust impinges on these wetted surfaces and is washed down. The air continues to swirl spirally in space A and throws the water that falls off of tube baffle 5^c to the adjacent wall 2 thus washing down dust that impinges thereon. The air is then deflected through the curved vanes 18^c into space B, thence spirally upward through each successive row of vanes 18^b and 18^a, meeting at each juncture the water that falls from annular water chamber 10 through water pipes 10¹ connected therewith. This annular water chamber 10 is supplied by water pipe 16¹ which extends through wall of chamber 2.

Thus it is seen that there are two water supplies. One supply through pipes 16 washes down the heavy dust particles into primary sludge cone 1 and then into secondary sludge chamber 18. The other supply through pipe 16¹ supplies clean fresh water for final cleaning of the air that passes up through the bladed sections. This makes it possible to recirculate the dirty water 35 that can be separated from the sludge that flows

through sludge outlet 21 from sludge chamber 18, without contaminating the clean air that flows out of the clean air outlet 14 and which has been washed by a separate supply of clean fresh water from pipe 16¹. Thus it is possible to use two separate washing liquids.

Having described my invention and its operation, I claim:

1. A gas-cleaning apparatus comprising a shell 10 provided with a tangential inlet near the top, a collector which creates an upper and lower compartment within the shell, an outlet for cleaned gases in the lower compartment, a vertical tube 15 open at both ends depending from the lower end of said collector, superposed ring-shaped baffles attached to the inner wall of said shell below said outlet and extending away from said wall superposed ring-shaped baffles of less diameter than the inner periphery of said first-mentioned 20 baffles attached to and surrounding the outer surface of said tube, in staggered relationship to said first mentioned baffles, means below said collector for supplying liquid to the space above said baffles, swirl-producing vanes circularly supported about the periphery of said last-mentioned baffles, each row of vanes extending vertically to a position adjacent and in spaced relationship to said first-mentioned baffles, so that portions of said liquid within the lower compartment may flow downwardly and between said baffles and swirl-producing means.

2. Apparatus as in claim 1 in which another independent means for supplying liquid is provided at the top of said shell.

ERNEST F. FISHER.
